CLOCK

Arno W. Fowler, Highland, Ill.

Application December 10, 1931

Serial No. 580,045

8 Claims. (Cl. 185—40)

This invention relates to clocks.

Objects of the invention are to provide gearing for winding the main spring of a clock, an electrically controlled oscillating device for winding the spring to a condition to operate the clock, and an improved mechanism for preventing said device from overwinding the spring; and to improve the mechanism controlling the extent to which the spring may be wound by providing a positive drive for said mechanism as contrasted with the mechanism disclosed in my copending application, Serial No. 568,280, filed October 12, 1931.

Other objects will appear from the following description, reference being made to the accompanying drawings, in which—

Fig. 1 is a view of the clock mechanism having the front frame plate removed and several of the arbors and shafts shown in section.

Fig. 2 is a side elevation of the clock.

Fig. 3 is a view from the rear, the rear frame plate of the clock being removed and several of the shafts being shown in section, and the device that operates the gearing to wind the clock spring being in position to operate said gearing.

Fig. 4 is a view similar to Fig. 3 with other parts removed and showing the winding mechanism in the position it occupies after an effective winding movement thereof.

Fig. 5 is an enlarged detail sectional view showing the gearing for winding the clock spring and the control device for preventing overwinding of the spring.

Fig. 6 is a sectional view of part of the circuit closer mechanism illustrating the devices by which the gear actuating device of the spring winding mechanism controls the electric circuit.

The time indicating mechanism of the clock is operated by a gear wheel 1 mounted for rotation on and about a rotary shaft 2. The usual hands of the clock (not shown) are mounted on spindles 3 and 4 rotated at different speeds by familiar trains of gearing operated by the gear wheel 1. A spring 5 has one end attached to a drum 6 rigid with the gear wheel 1 and the opposite end attached to the shaft 2. The clock, of course, includes the usual escapements and control devices (not shown) for rotating the spindles 3 and 4 at proper speed by the slow rotation of the gear 1 by the spring 5. The spring 5 is wound by rotating the shaft 2 in the proper direction relative to the gear 1 and unwinds to rotate the gear 1 while the shaft 2 remains stationary.

The present invention comprises mechanism for winding and tensioning the spring 5 and maintaining said spring 5 at approximately uni-

form tension at all times. Further, the invention comprises means for maintaining an approximately uniform storage of power and energy in the spring 5, so that in event of interruption of the frequent operation of the winding mechanism, said spring 5 will continue to operate the clock for a considerable period of time. This prevents the clock from stopping in event of the interruption of the continuity of electric energy.

A gear wheel 7 is attached to the shaft 2 and is in constant mesh with a pinion 9 attached to a rotary shaft 10. A ratchet gear 11 is attached to the shaft 10 adjacent to a lever 12 having a hub 13 pivoted on said shaft. A pin 14 attached to the lever 12 projects therefrom parallel with the shaft 10. A pawl 15 pivoted on a support 16 engages the peripheral teeth on the ratchet wheel 11 and prevents said ratchet wheel from being turned in a reverse direction by the power and energy of the spring 5 exerted through the shaft 2, the gear 7, the spindle 9, and the shaft 10. A pawl 17 pivotally supported by the lever 12 is held in engagement with the peripheral teeth of the ratchet wheel 11 by a spring 18. Thus, the lever 12 and the pawl 17 constitute means for rotating the ratchet wheel 11 and thereby the shaft 10, the spindle 9, the gear wheel 7 and the shaft 2 effectively to wind the spring 5.

An electro-magnet device 19 is mounted in connection with the clock and has cores 20 which are energized when the electric circuit through the electro-magnet is closed. An electric circuit wire 21 is connected to one end of the electro-magnet 19 and said magnet is electrically connected with the frame of the clock 20 by a wire 22.

A metallic lever 23 is pivotally supported by a pivot 24 and at its lower end supports a metallic member 25. A metallic spring 26 is attached to the side of the metallic member 25 that is toward the cores or armatures 20 and said spring is effective when the electric circuit is broken to impart an impulse to the lower end of the lever 23 to initiate a movement to separate the member 25 from the armatures 20.

The other wire 27 of the electric circuit is connected with a metallic terminal fastener plate 28 attached to and insulated from the upper end of the lever 23. The upper end of the lever 23 has a laterally bent portion 29. Metallic screws 30 pass through the metallic terminal plate 28 through insulation plugs 31 through an insulation plate 32 and are engaged with a metallic plate 33. Thus, the metallic plate 28 is in electrical communication with the 110

plate 33 through the screws 30, but is out of electrical communication with the lever 23 and the part 29 of said lever.

A metallic contact member 34 (Figs. 3 and 8) 5 is attached to the metallic plate 33 and thus in electrical communication with the metallic terminal plate 28 and is out of electrical communication with the lever 23. This is true because the insulation plugs 31 support the screws 30 10 out of electrical communication with the part 29 of the lever 23.

An actuator 35 is attached to the free end of the lever 12. As shown, this actuator is a weight, which is sufficient to operate the lever 12 downwardly and thereby rotate the ratchet wheel 11 15 in a direction to wind the spring 5 in the manner described, whenever said lever 12 is raised and said spring is tensioned or wound below a predetermined minimum.

20 The lever 23 occupies an inclined position, so that the weight of the parts 28, 29, 30, 31, 32, 33 and 34 at the upper end of said lever is utilized as an actuator to actuate said lever to a position and to an extent in which the member 25 is spaced from the ends of the cores or armatures 20. So long as the wire 27 is out of electrical communication with the frame of the clock, the electro-magnet 19 will not be energized. The means for placing the wire 27 in 25 electrical communication with the frame of the clock and thus closing the circuit and energizing the electro-magnet 19 is an important feature of the present invention.

The relationship of the parts is such that 30 when the part 35 is seated upon its supporting rest 36, the pin 14 is in contact with the contact member 34. Thus, whenever the lever 12 moves downwardly to the full extent that it may move, the electric circuit is automatically 35 closed, the electro-magnet 19 is energized, the lever 23 is thereby operated by moving the lower end of said lever toward the cores or armatures 20 and moving the upper end of said lever in a direction and to an extent to raise 40 the lever 12 from its lower position, shown in Fig. 4, to its upper position, shown in Figs. 1, 3 and 6. The pin 14 is utilized as a crank against which the contact member 34 presses and operates as required to raise the free end of the 45 lever 12. This action of the lever 23 whenever the electro-magnet 19 is energized is sudden, so that a quick impulse is imparted to the combined crank and contact pin 14 sufficient to 50 throw said contact pin considerably beyond and out of contact therewith and substantially to 55 the position shown in Fig. 3. This breaks the electric circuit and permits the lever 12 to move downwardly as the spring 5 unwinds until said lever again moves the pin 14 into contact with 60 the member 34, whereupon the operation is repeated.

65 My invention comprises means limiting extent to which the spring 5 may unwind and also limiting the extent to which said spring may be wound up. The means for thus limiting and controlling extent of winding and unwinding of the spring 5 comprises mechanism associated and combined with the wheels 1 and 11. This mechanism is 70 operated by the wheel 1 so as to stop further rotation of said wheel 11 and thereby stop further winding of the spring 5 when said spring 5 is wound a predetermined extent. Said mechanism is operated by the wheel 1 to release the wheel 75 11 and permit further operation of the spring

winding mechanism when the spring unwinds a predetermined extent.

A hub 37 is rigidly attached to the wheel 1 for rotation thereby and is exteriorly threaded. A gear wheel 38 is screwed on the hub 37. The gear wheel 38 has the same diameter as the gear wheel 7 and is in constant mesh with a long pinion 39 attached to the shaft 10. The pinion 39 is of the same diameter as the pinion 9.

A brake element 40 is mounted for sliding movements in the clock frame member 41 and has its axis parallel with the axes of the shafts 2 and 10. An end 42 of the brake element 40 is adapted to be moved into and out of frictional engagement with the ratchet wheel 11. The end of the brake element 40 opposite from the end 42 is adjacent to a presser plate 42' supported for sliding movements along the shaft 10 and the hub 37. The lower end of the plate 42' is alongside of the hub 38' of the gear wheel 38.

It is now clear that when the shaft 10 is rotated by the operating mechanism, both of the gears 7 and 38 are rotated in the same direction and at the same rate of speed. Rotation of the gear 7 rotates the shaft 2 and thereby winds the spring 5 while rotation of the gear 38 screws said gear along the hub 37 and causes the hub 38' of said gear to press against the plate 42' and actuate said plate to force the clutch brake element 40 into frictional braking engagement with the ratchet wheel 11. The parts are arranged in such relationship that when the spring 5 is wound to a predetermined degree of tension beyond which no further winding of the spring is to be permitted, the brake element 40 has engaged the ratchet wheel 11 with sufficient force and pressure to prevent rotation of said wheel 11 by the actuating mechanism.

Rotation of the gear wheel 1, which operates the time indicating mechanism of the clock, is 115 continued by the spring 5 and the threaded hub 37 is rotated by said gear wheel 1 while the ratchet wheel 11 is held by the brake element 40 from rotation. The pinions 9 and 39 also remain stationary so long as the ratchet wheel 11 remains 120 stationary. Accordingly, both gear wheels 7 and 38 are held from rotation. The fact that the gear wheel 38 is held stationary while the threaded hub 37 is rotating causes the threads whereby the hub 37 engages the gear wheel 38 to move said 125 gear wheel 38 along the hub 37 toward the wheel 1, thus releasing the brake member 40 after said gear wheel 38 has moved a predetermined extent toward the gear wheel 1. After the brake member 40 has been released, the actuator 12—35 130 may again operate effectively to rotate the ratchet wheel 11 and thereby the shaft 10, the pinions 9 and 39, and gears 7 and 38 while the gear 1 is held by the familiar clock gearing from rotation with the gears 7 and 38.

135 As shown, extent of downward movement of the lever 12 is limited by the supporting rest 36 and extent of upward movement of said lever is limited by a yielding abutment 43.

As shown in Fig. 3, the lever 23 is supported 140 in its idle or unoperated position by a spring 44 on said lever engaging a stationary support 45 mounted on the clock frame. The lever 12 will move downwardly from the position shown in Fig. 3 until the contact pin 14 is moved into contact with the contact member 34 to close the circuit through the electro-magnet. The spring 44 is shown supporting the lever 23 in order that the pin 14 will contact with the contact member 34 before the part 35 engages the support 36. 150

Such contact of the contact members 14 and 34 closes the electric circuit and causes the electromagnet 19 to become energized. The lever 23 is thereupon operated and the pin 14 and its relationship to the lever 12 are utilized as a crank device to raise the lever 12 to its upper position against the yielding abutment 43. As stated before, this operation of the lever 23 is quick and sudden, so that the pin 14 is thrown beyond and 10 out of contact with the contact member 34, thus breaking the circuit and permitting the spring 26 to move the member 25 immediately out of contact with the core or armature member 20. This 15 also moves the upper end of the member 23 to its unoperated position in which the spring 44 engages the abutment 45. The pawl 17 is constantly engaged with the ratchet wheel 11. The actuator device 35—12 moves downwardly until the spring 5 is wound to the predetermined tension, or until 20 the contact pin 14 is engaged with the contact member 34, or until the brake member 40 engages and stops rotation of the ratchet wheel.

It is now clear that my present invention comprises a lever for operating a train of gearing to 25 wind the spring 5; that the movement of said lever in one direction is controlled and permitted by the unwinding of said spring; that the movement of said lever in said one direction to a predetermined position controls the energizing of the 30 actuator 19 and consequent operation of the lever 23 to move the lever 12 to a position in which it will operate the train of gearing to rewind the spring; and these winding operations continue until the spring 5 is rewound to the proper degree of tension, or until further operation of the 35 winding operation is stopped and prevented by the brake device 40. Consequently the invention obtains all of its stated and other intended objects and purposes in a highly efficient and 40 satisfactory manner and may be varied as widely as the scope of equivalent limits will permit without departure from the nature and principle of the invention. I do not restrict myself in any unessential respects, but what I claim and desire 45 to secure by Letters Patent is:

1. Mechanism of the character described comprising a shaft, a gear supported for rotation around said shaft, a spring connecting said gear and said shaft, an additional shaft supported 50 parallel with said first shaft, mechanism for rotating said additional shaft, gearing operated by said additional shaft for rotating said first shaft to wind said spring, a gear having threaded connection with said first gear, means for rotating 55 said second gear by said second shaft, and means operated by said second gear for preventing operation of said mechanism.

2. In a clock having a shaft, a gear wheel supported for rotation around said shaft, and a 60 spring for rotating said gear wheel and having one end attached to said shaft and the other attached to said wheel; a threaded hub rigid with said gear wheel, a gear screwed on said hub, a shaft parallel with said first shaft, mechanism for rotating 65 said second shaft, gearing operated by said second shaft for simultaneously rotating said first shaft and said second gear wheel relative to said first gear wheel to wind said spring, and a device operated by said second gear wheel for stopping 70 operation of said mechanism when said spring has been wound to a predetermined degree of tension.

3. In a clock having a shaft, a gear wheel mounted for rotation about said shaft, and a 75 spring connecting said shaft and said gear wheel

for rotating said gear wheel while said shaft remains stationary; gearing for rotating said shaft to wind said spring, a second gear wheel, a threaded hub rigid with said first gear wheel screwed into said second gear wheel, gearing for 80 rotating said second gear wheel simultaneously with the rotation of said shaft by said first gearing and for holding said second gear wheel against rotation by said first gear wheel, a shaft for rotating said two gearings, and a device operated by said second gear wheel for limiting extent of rotation of said second gear wheel and preventing overwinding of said spring.

4. In a clock, a shaft, a gear wheel mounted for rotation around said shaft, a spring connecting said gear wheel and said shaft, a winding gear attached to said shaft, a driving shaft parallel with said first shaft, mechanism for rotating said driving shaft, a pinion attached to said driving shaft for rotating said winding gear and thereby said first shaft to wind said spring, an additional pinion rigid on said driving shaft, a controlling gear wheel meshing with said additional pinion, a threaded hub rigid with said first gear wheel on which said controlling gear wheel is screwed, and means operated by said controlling gear wheel controlling rotation of said additional shaft.

5. In a clock having a shaft, a gear wheel supported for rotation around said shaft, and a spring for rotating said gear wheel and having one end attached to said shaft and the other end attached to said gear wheel; a threaded hub rigid with said gear wheel, a gear screwed on said hub, a shaft parallel with said first shaft, gearing operated by said second shaft for simultaneously rotating said first shaft and said gear relative to said gear wheel to wind said spring and to move said gear along said hub, and an element operated by said gear into engagement with a part 100 of said gearing to stop operation of said gearing when said spring has been wound to a predetermined degree of tension.

6. In a clock having a shaft, a gear wheel loosely mounted on said shaft for rotation around said shaft, and a spring engaging said gear wheel and said shaft for rotating said gear wheel; a threaded hub rigid with said gear wheel, a gear screwed on said hub, a driving shaft parallel with said first shaft, mechanism for rotating said driving shaft, gearing operated by said driving shaft for rotating said first shaft to wind said spring, additional gearing operated by said driving shaft for rotating said gear that is screwed on said hub, and a device operated by said last named gear controlling operation of said mechanism.

7. In a clock, a rotary gear wheel, a spring for rotating said gear wheel, a threaded hub rigid with said gear wheel, a gear screwed on said hub, mechanism for holding said gear from rotation with said gear wheel and causing said threaded hub to move said gear toward said gear wheel, means for operating said mechanism to rotate said gear and to cause said gear to move in a direction away from said gear wheel, means operated by said mechanism for tensioning said spring, and a device operated by said gear for stopping operation of said operating means when said spring has been wound to a predetermined degree of tension.

8. In a clock, a rotary gear wheel, a spring for rotating said gear wheel, a threaded hub rigid with and rotated by said gear wheel, a gear screwed on said hub, mechanism holding said

- gear from rotating and causing said gear to screw along said hub toward said gear wheel when said gear wheel is rotating and said mechanism is stationary, means for rotating said mechanism to rotate said gear and cause said gear to screw along said hub in a direction away from said gear wheel, and a brake device operated by said gear during movement of said gear away from said gear wheel as aforesaid to stop and prevent operation of said operating means. 80
